CLAIM

I claim the ornamental design for a drinking training spout, as shown.

DESCRIPTION

FIG. 1 is a perspective view from above of a drinking training spout in accordance with the design;

FIG. 2 is a perspective view from below thereof;

FIG. 3 is a bottom view thereof;

FIG. 4 is a left side sectional view taken from FIG. 3;

FIG. 5 is a front elevation sectional view taken from FIG. 3;

FIG. 6 is a rear elevation view thereof;

FIG. 7 is a left side view thereof;

FIG. 8 is a right side view thereof; and,

FIG. 9 is a front elevation view thereof.

Those features depicted with dashed lines do not form a part of the disclosed design.
